UNITED STATES PATENT OFFICE.

CONRAD FARNER, OF MILWAUKEE, WISCONSIN.

WRENCH.

SPECIFICATION forming part of Letters Patent No. 355,444, dated January 4, 1887.

Application filed June 21, 1886. Serial No. 205,765. (No model.)

To all whom it may concern:

Be it known that I, CONRAD FARNER, of Milwaukee, in the county of Milwaukee and State of Wisconsin, have invented new and useful Improvements in Wrenches; and I do hereby declare the following to be a full, clear, and exact description of said invention, reference being had to the accompanying drawings, and to the letters or figures of reference marked thereon, which form a part of this specification.

My invention consists in the peculiar form and construction of the parts of the device to which it relates, and in the arrangement and adjustment of these parts with reference to each other.

In the drawings, Figure 1 is an elevation of a wrench embodying my invention, parts being broken away to expose interior parts to view. Figs. 2, 3, and 4 are details.

A straight bar, A, is provided with a face on its outer end adapted to serve as one of the jaws of the clutch of the wrench. This face is preferably roughened or serrated, furnishing a friction-surface of great power. On the rear or top side of the bar A is a serrated or toothed rack, C, for the use hereinafter stated.

B is a sleeve fitted to and sliding freely on the bar A. An independent jaw, E, the face F of which is located in front of and opposite to the face B, is preferably roughened or serrated, furnishing a powerful friction-surface. The jaw E has a rearwardly-extending arm, G, which is pivoted in the top of the sleeve D, whereby the jaw E is permitted to swing outwardly and inwardly from and to the face B of the bar A.

A small coiled-wire spring, H, is preferably inserted between the rear end of the arm G and the top of the sleeve D, whereby the jaw E is held yieldingly to position directly in front of the face B.

In the top of the sleeve D, opposite to the rack C, there is an aperture, I, in which a latch or stop-block, J, is fitted and moves freely in and out. This block J is provided in its bottom or inner surface with teeth and grooves corresponding with those in the rack C, whereby this block is adapted to clutch with the rack C and hold the sleeve D firmly in position on the bar A. The block J is also provided with a longitudinal aperture, K, into

which the key L is inserted through an aperture, M, therefor in the end of sleeve D, in which aperture and in the corresponding aperture, N, in the end of sleeve D at the further side of aperture I the key L is supported and rotates.

A feather, O, which forms a part of the key L, is adapted to impinge against the walls of the aperture K, which aperture K is so located in the block that when the feather O is turned down toward the bar A it forces the block J against and locks it upon the bar A.

The key L is operated by means of the handle P, the form of which is immaterial. For convenience in building and handling the wrench, I preferably construct the handle Q separately from the bar A, and attach them together by a male and female screw or other equivalent means, though the handle may readily be made simply an extension of the bar A.

By reason of the sliding movements which the sleeve D and the thereto-attached jaw E has on the bar A, this device is adapted to grasp nuts or bolts of varying sizes, and by reason of the additional swinging motion of the jaw E, and the angular clasping-power thereby provided for, this device is also adapted for use as a pipe-wrench.

What I claim as new, and desire to secure by Letters Patent, is—

1. In a wrench, the bar A, the thereon-formed rack C, and the sleeve D, sliding on arm A and supporting the thereto-pivoted arm G, in combination with the movable stop-block J, the key L, and feather O thereon, all constructed and arranged substantially as described.

2. The combination of a bar, A, having a face on its outer end and a rack, C, on its back, with the swinging arm G, having a jaw-face, F, the movable sleeve D, to which the arm G is pivoted, the spring H, inserted between the rear end of arm G and sleeve D, movable stop-block J, and the therein-inserted key L, having feather O, all substantially as described.

In testimony whereof I affix my signature in presence of two witnesses.

CONRAD FARNER.
